UNITED STATES PATENT OFFICE.

PRESTON GEE HATCHER, OF JONESBORO, ARKANSAS.

BANANA CRATE.

Application filed October 18, 1921. Serial No. 508,544.

To all whom it may concern:

Be it known that I, PRESTON GEE HATCHER, a citizen of the United States, and a resident of Jonesboro, in the county of 5 Craighead and State of Arkansas, have invented certain new and useful Improvements in Banana Crates, of which the following is a specification.

This invention relates to wooden receptacles, and more particularly to an improved crate especially adapted for shipping bananas or the like such as when the bananas are shipped in a bunch on the stalk.

The primary object of the invention is to 15 provide a folding crate especially adapted for shipping bananas as specified and which may be readily folded or collapsed so as to occupy a minimum amount of space when returned and which at the same time may be 20 very economically produced as well as presenting a ready-built construction which is both strong and durable so as to withstand rough usage in shipment and more adaptable for general use and for packing purposes, said crate being provided with a bottom portion and an inside hoop at the top adapted to maintain the crate or basket in an open or extended position, as well as permitting the lining thereof with paper and 25 the provision of a top of plain wood, basket material such as reed or other woven material of a similar character, paper or cloth, either of these materials working successfully with the construction illustrated, with- 30 out the necessity of employing expensive hooks, hinges, or fasteners of any sort.

Other and further objects of my invention will become readily apparent to persons skilled in the art, from a consideration 40 of the following description when taken in conjunction with the accompanying drawings, wherein:

Figure 1 is a perspective view of the improved banana crate folded or collapsed.

Figure 2 is a longitudinal sectional view thereof showing the crate extended or set up for use, and

Figure 3 is a top plan view thereof.

Referring to the drawings in detail, in 50 which like reference characters designate corresponding parts throughout the several views, my improved banana crate is shown as comprising a series of longitudinal staves or strips 10 preferably of relatively thin and light wood or the like, in the manner of barrel staves, but disposed in upwardly

branching or divergent relation from the bottom portion 11 preferably consisting of a solid piece of wood of circular or other form in plan, thus providing intervening 60 spaces 12 enlarging in width toward the top of the crate. The staves or strips 10 are connected at a plurality of spaced points preferably at the ends or top and bottom portions of the crate and intermediately at 65 equi-distantly spaced points by means of flexible strips or hoops 13 of narrow and thin strips of strap iron or tin, preferably painted to protect the same from rusting and having the ends thereof secured in overlapping relation to the staves as indicated at 14, staples or the like 15 being employed for securing said hoops to all of the staves.

In this manner, owing to the flexibility or bendable character of the hoops, the crate 75 may be readily collapsed from the extended or open position of circular cross section or the like, as shown in Figures 2 and 3, to the relatively flat form shown in Figure 1 of the drawing. The bottom portion 11 is secured 80 to the inside of one of the staves by a flexible strip of sheet metal as indicated at 16, thus forming a hinge for the bottom which may be swung between the staves when collapsed, in the manner shown in dotted lines 85 in Figure 1 of the drawing from the position shown in Figure 2. The strip is secured to the side of the stave and to the top face of the bottom portion 11 and will readily bend to permit the folding thereof as shown in 90 Fig. 1, or to allow the same to drop or to be folded down to the position shown in Figure 2 in order to hold the crate in position and at the same time form a bottom for supporting the bananas or other material 95 shipped therein. In order to limit the movement of the bottom to the position shown in Figure 2, a plurality of lugs or stops 17 are provided, the same consisting of strips of sheet metal rebent upon themselves inter- 100 mediately as shown at 18, said rebent portion being offset inwardly to form shoulders while the leg portions are disposed in contact as indicated at 19 and secured by a common securing means to certain of the 105 staves in spaced relation around the interior of the same in spaced relation to the bottom thereof or the lower ends of the staves, thus sustaining the bottom in position.

At the top the crate is provided with an 110 inside hoop or frame ring 20, the overlapping portions of the strip of wood forming

the same being secured together as indicated at 21 and hinged to the same stave as the bottom portion by a flexible metallic or sheet metal strip 22 extending inwardly, said strip being secured to the outer face of the ring or hoop 20 and to the side of the stave so as to permit the hoop to bend inwardly to the position shown in Figure 1 of the drawings, when the crate is collapsed or 10 to be extended against the other staves in order to hold the crate in form in conjunction with the bottom plate as heretofore described. In order to hold the hoop 20 in this position, a plurality of clips 23 are 15 secured to spaced staves of the crate at the outside thereof and are in the form of doubled or relatively stiff sections of sheet metal secured against the outer faces of the same as indicated at 24 and bent over the 20 top edges thereof and downwardly and inwardly in spaced relation thereto as indicated at 25 in Figure 3 so as to receive the hoop 20 beneath the same, that is between the downwardly and inwardly bent 25 portions forming the clips proper and the inner faces of the staves so as to frictionally hold and retain the hoops in this position as clearly shown in Figures 2 and 3 of the drawings.

30 A lining of paper or the like indicated at 26 is provided for the interior of the crate 26 preferably for the upper portion thereof and preferably consists of two sections or strips or a top of cloth or paper wound around 35 and pasted to the hoop 20 as indicated at 27, and the top of the crate may be disposed in any suitable manner as by a circular piece of wood corresponding to the bottom portion 11, top of basket material such as reed, 40 or of paper or cloth. It will be seen that the construction described obviates the necessity of employing expensive hooks, fasteners or hinges of any sort and the device is therefore extremely light in weight and 45 may be easily collapsed or set up for use.

In view of the foregoing it is thought that the operation of the device will be readily apparent and in view of the simplicity and practical value that it will readily commend itself to those skilled in the art.

Having thus described my invention what I claim is:—

1. A crate of the class described comprising staves extending longitudinally of the crate, flexible strips encircling and connecting the staves, a bottom hinged to one of the staves at the inside and collapsible therewith, said bottom being adapted to be opened out to hold the crate in form, and 55 a hoop at the top of the crate hinged to a stave, and adapted to hold the top portion 60 of the crate in extended form.

2. A crate of the class described comprising staves extending longitudinally of the crate, flexible strips encircling and connecting the staves, a bottom hinged to one of the staves at the inside and collapsible therewith, said bottom being adapted to be swung outwardly to hold the crate in form, a hoop hinged to a stave adjacent the upper 65 end thereof and to the inside thereof to swing inwardly in opposite direction to the swing of the bottom portion, when the staves are collapsed together with the flexible strips thereof, a lining and top portion engaging 70 said hoop, and clips carried by certain of the staves and disposed in spaced relation to the inside of said staves to receive and hold frictionally said hoop therein when the 75 crate is extended.

3. A crate of the class described comprising staves extending longitudinally of the crate, flexible strips encircling and connecting the staves, a bottom hinged to one of the staves, at the inside and collapsible 85 therewith, said bottom being adapted to be opened out to hold the crate in form, and a hoop at the top of the crate and also hinged to the same stave that the bottom is hinged to, and adapted to hold the top portion of 90 the crate in extended form.

4. A crate of the class described comprising staves extending longitudinally of the crate, endless flexible strips encircling and connecting the staves, a bottom hinged 95 to one of the staves at the inside and foldable thereon, said bottom being adapted to be swung outwardly to hold the crate in form, a top bracing member hinged to the same stave as the bottom and disposed adjacent the upper end thereof to collapse 100 with the staves and within the body portion or to hold the top portion in an extended position by engagement with the inner faces 105 of the staves, and means to hold the same in an extended position.

5. A crate of the class described comprising staves extending longitudinally of the crate, flexible strips encircling and connecting the staves, a bottom hinged to one 110 of the staves at the inside and collapsible therewith, said bottom being adapted to be opened out to hold the crate in form, a hoop hinged to the same stave as the bottom and at the inside thereof to fold inwardly in 115 opposite direction from the direction of fold of the bottom portion when the staves are collapsed together with the flexible hoops thereof, a lining and top portion engaging said hoops, and clips carried by certain of 120 the staves and disposed in spaced relation to said staves at the inside to receive and hold said hoop therein when extended.

PRESTON GEE HATCHER.
